UNITED STATES PATENT OFFICE.

HORACE S. GARR, OF LOS ANGELES, CALIFORNIA, ASSIGNOR OF ONE-HALF
TO REUBEN JAY TARBELL, OF SAME PLACE.

BURNING AND HEATING APPLIANCE.

SPECIFICATION forming part of Letters Patent No. 599,499, dated February 22, 1898.

Application filed May 27, 1895. Serial No. 550,763. (No model.)

To all whom it may concern:

Be it known that I, HORACE S. GARR, a citizen of the United States, residing at Los Angeles, in the county of Los Angeles and State 5 of California, have invented a new and useful Burning and Heating Appliance, of which the following is a specification.

One object of my invention is to provide simpler and better means for producing complete combustion, doing away with deposits 10 of soot and entirely consuming the fuel used.

My invention is also applicable for burning oil, wood, coal, and other fuel. (If oil is burned, a suitable oil-burning appliance 15 should be used.)

The object of my invention is to provide a very simple device for burning smoke and economizing fuel and which device is applicable for cooking and heating stoves, for 20 crematories, bake-ovens, steam-boilers, and water-heaters, and other uses pertaining to burning and heating.

My invention comprises a stove or furnace provided with a combustion-chamber consisting 25 of a hollow triangular prism.

My invention also comprises the combination of a fire-box having an air-inlet, a hollow triangular prism communicating with the rear end of said fire-box through a contracted 30 opening in the front end of the prism and having a suitable outlet for the products of combustion at the rear end of the prism, and an air-inlet into the prism at the front end.

My invention includes a furnace having 35 between its fire-box and chimney a combustion-chamber which consists of a hollow triangular prism provided in each of its ends with a centrally-arranged circular opening inscribed within a triangle which is approximately one-fourth the cross-sectional area 40 of such prism and which openings communicate, respectively, with the fire-box and chimney.

An important object of my invention is to 45 provide a simple contrivance which will receive the products of partial combustion which result from the ignition of fuel in the fire-box of the furnace and to cause an action and reaction of such products and admit air 50 to the unconsumed products and mix and mingle them at once, so as to induce a com-

plete transformation of such fuel into heat energy and to then apply such heat energy in great volume and with great intensity to the object to be cooked or incinerated and to do 55 this with the greatest possible economy and least expensive structure; also, to produce the greatest concentration of heat in the oven where it may be desired to bake or incinerate various objects—as, for example, in bakers' 60 ovens, potters' furnaces, and crematories.

I apply the heat to the oven or incinerating-chamber from combustion-prisms which surround the oven or incinerating-chamber at the sides thereof and communicate with 65 the fire-box at one end of the apparatus and with the chimney at the other end of the apparatus and into which prisms the air is admitted and whereby an intense heat is applied where required.

The accompanying drawings illustrate my invention in one mode of applying it in a stove for heating and cooking purposes and also one mode of applying it for crematories. The 70 crematory illustrated is suitable for incineration of human bodies. The insulating-casing of brick or other suitable material, which will be applied outside the inclosing prism, is not shown. The same can be applied without the exercise of any inventive faculty.

Figure 1 is a fragmental side elevation of a crematory embodying my invention, the insulating-brickwork being omitted and portions of the apparatus being broken away to expose interior structure. Fig. 2 is a fragmental vertical section of my new crematory through the prisms and incinerating-chamber, looking toward the fire-box or furnace. Line 2 3, Fig. 1, indicates the line of section. Fig. 3 is a like section of the crematory, looking 75 toward the chimney, which leads from the prisms, and toward the door, which opens into the oven or incinerating-chamber. Fig. 4 is a fragmental front elevation of the crematory, broken away in part to show interior structure. Fig. 5 is longitudinal vertical section of a heating or cooking stove in which my invention is applied. Fig. 6 is a front elevation of the same, parts being broken away to expose interior structure. Fig. 7 is 80 a plan view of the stove. Fig. 8 is a transverse section on line 8 8, Fig. 5, cutting 85 90 95 100

- through the oven and prism. Fig. 9 is a detail of the damper controlling the entrance of air into the inlet between the fire-box and the auxiliary combustion chamber or prism.
- 5 A indicates the fire-box in the crematory. A' indicates the fire-box in the stove. B B' B'' indicate the prisms in the crematory, and B''' indicates the prism in the cooking-stove. These constitute the auxiliary combustion-chambers.
- 10 C indicates the chimney of the crematory, and C' indicates the chimney, stovepipe, or other suitable outlet for the products of combustion from the stove.
- 15 15 In the crematory or other heating appliance in which I wish to concentrate heat in an oven or heating or incinerating chamber I arrange three of the triangular prisms in a triangular figure, so as to form between three 20 of the faces of said prisms a chamber or space E, leaving openings e between the adjacent edges of the prisms.
- F indicates an inclosing shell or case prism, which in case of the triangular arrangement 25 above set forth is preferably triangular in cross-section and incloses the prisms in which the final combustion is to take place, leaving a heating-space G around the prisms inside of the walls of the inclosing prism.
- 30 30 H H' H'' H''' indicate the inlets into the front ends of the combustion-prisms from the fire-box or furnace. h h' h'' h''' indicate air-inlets into the front end of the prism. In the drawings I have 35 shown the air-inlets entering into and through the inlets H, H', H'', and H'''. I I' indicate dampers for opening and closing these inlets.
- In the crematory or bake-oven shown in 40 Figs. 1 to 4, inclusive, J J' indicate pan or grate brackets or supports on the lower combustion-prisms, and K indicates a pan or grate for supporting the body or other object during incineration or while being acted upon 45 by the heat for baking or for other purposes.
- 45 45 In case a grate is used a pan K' at the bottom of the central chamber will catch any ashes which may fall through. K'' indicates a door through which to withdraw the pan K'.
- 50 50 The prisms are made of steel, iron, or other suitable heat-conducting material, so that the heat is conducted through the same and radiated therefrom.
- 55 It might be found necessary in some instances where a very high degree of heat is required—as, for instance, in cremating human bodies—that the prisms be made of fire-clay to withstand the intense heat.
- 60 L indicates supports and stays for the prisms in the crematory.
- In the drawings I have shown the inclosing prism or case of the crematory thin in cross-section. It is to be understood that this thin case is to be bricked in or otherwise insulated, so as to prevent the escape of heat. I propose to make the space G between the combustion-prisms and the inclosing prism

or case about three inches across; but this may be increased or diminished, as may be found desirable. The purpose of this inclosing heat-space around the prisms is to allow the heat from the outer faces or sides of the prisms to be communicated to the inner chamber. The entire chamber within the inclosing prism or case is tightly closed, no opening being provided thereto excepting the door-openings M and K', which are hermetically closed when the crematory is in operation, and two other small openings which I will describe.

M' indicates a door for hermetically closing the entrance to the oven or incinerating chamber.

N indicates a small air-inlet into the oven, and O indicates a small fumes-outlet from the oven into the upper combustion-prism. In practice the air-inlet N allows the ingress of a small amount of air, and the outlet O allows the egress into the upper prism of the fumes from the oven, so that the fumes will 90 be carried into and will be consumed by the intense heat within the upper prism.

n indicates a damper to close the air-inlet N.

In the crematory the air is admitted into 95 the combustion-prisms through the pipes h h' h'', communicating with the outside atmosphere and leading, respectively, to other pipes P P' P'', which respectively surround and communicate with the inlets H H' H'', which 100 communicate between the fire-box and the combustion-prisms, respectively, so that the air is introduced into each combustion-prism through the inlet through which the products from the fire-box enter into such combustion-prisms, so that the air is fed to the unconsumed products in the most effective manner to produce final and complete combustion in the combustion-prisms.

p p' indicate inlets into the pipes or inlets 110 H, &c., from the pipes P, &c.

In practical operation there is produced in the central chamber E of the oven an intense concentration of heat upon the article placed in such chamber, so that a rapid and complete incineration of any animal or vegetable combustible placed therein will result.

In an ordinary cooking-stove or bake-oven one combustion-prism B'', as shown in Figs. 5 and 8, is sufficient for all practical purposes, and this I arrange at the bottom of the oven, with one of the flat faces uppermost. I also provide beneath and at the side of the fire-box auxiliary oven-chambers 2, communicating with the oven, so that all of the heat 120 both of the first and partial combustion in the fire-box and of the subsequent complete combustion in the prism will be utilized for baking and other purposes. In the stove the top is formed of a single sheet or plate 3 of 130 metal, and cooking can be done on the same. Different degrees of heat will be furnished by different parts of the plate, that over the fire-box being the greatest and that over the aux-

iliary oven-chamber the least. I prefer to make the top of the stove over the fire-box and the auxiliary oven-chamber plain and flat and without openings for kettles. I prefer to use flat-bottom utensils 4 to sit upon the stove. In addition to this I deem it advisable to use square utensils, as shown in Fig. 7, for heating water or for like purposes for the reason that the greater portion of the 10 heating-surface of the top of the stove can thus be utilized.

The combustion-prism B''' inside of the stove-oven is arranged with one of its flatsides uppermost, and the articles to be cooked can 15 be placed directly upon the prism or can be held up above by some suitable support.

R indicates a deflecting-plate within the oven above and resting upon the combustion-prism to deflect the heat and prevent burning 20 upon the bottom of articles being baked and to provide for more uniform cooking.

S indicates reflectors arranged at the top of the oven to reflect and deflect the heat down upon the articles to be cooked. These have 25 their counterpart in the oblique inside faces of the inclosing prism of the crematory.

T indicates covers to be placed over utensils on the top of the stove while the same are being heated. These covers are open at 30 the bottom and fit upon the top of the stove, thus to retain the heat and insulate the vessels from the outside air.

U indicates a reservoir above the top of the oven for heating water.

35 V indicates a flue extending under the bottom of the water-reservoir, between it and the oven. This flue connects with the stovepipe or chimney C'.

W indicates a damper in the stovepipe or 40 chimney above the flue V to turn the draft into the flue.

X indicates a series of prisms in the reservoir, extending from front to rear and communicating with the flue V at its front end 45 and with the stovepipe or chimney above the damper.

Y indicates a damper in the flue V.

When the damper W is open, the draft goes up the stovepipe direct and when the 50 damper Y is open and W is closed it will cause the draft to pass through the flue beneath the water-reservoir and then through the prisms, thus heating the water in the reservoir.

55 Z indicates a door at the ends of the prisms. I have only shown these appliances attached to the stove, but it is to be understood that they can be applied to the device which is shown as a crematory. The device shown as 60 a crematory is adapted for baking, &c., and where it is thus used the water-heating appliance would be a valuable adjunct.

In practical operation the fire is applied in the fire-box and the fuel ignited, and the partially-consumed products of combustion pass 65 through the contracted opening into the auxiliary combustion-chamber, being mingled

with air which is admitted at the front end of such chamber. The newly-admitted air and the heated products of the partial combustion 70 become thoroughly intermingled and complete combustion ensues, and the resultant products pass out through the outlet at the other end of the combustion-chamber, except that the greater portion of the heat is radiated 75 from the combustion-chamber into the oven which contains it. In the case of an oven having three triangular combustion-prisms, as shown in Figs. 1 to 4, inclusive, any degree 80 of heat, from a moderate to a very intense heat, depending on the amount of fuel used, can be brought to act upon any object which may be upon the grate to heat, bake, or consume it. In case of cremating human bodies or other substances air will be admitted into 85 the oven through the air-inlet N, so that the gases will be carried up through the outlet O into the upper prism, thereby being consumed.

7 indicates a hot-air flue leading from the oven in the stove and controlled by a damper 90 8. This is to serve as a vent, in case it is too hot in the oven, to let the hot air out.

9 indicates a thermometer for indicating the temperature of the oven.

10 is a glass door to enable the cook to observe the processes of cooking taking place 95 inside of the oven.

When the fire is burning in the fire-box, the draft passes through the contracted inlet into the triangular combustion-prism and on 100 through such prism and strikes against the end thereof and reverberates and eddies and then passes out through the outlet at the other end, producing within the prism an eddying and a reverberation of the contents of 105 the prism. The reverberation is violent, both endwise and transverse, and there is a more thorough mixing and mingling of the air, and I believe there is produced a more complete and rapid combustion than can otherwise be 110 accomplished by use of as simple means, and at the same time an intense heat is produced in the incinerating-chamber between the several combustion-chambers, where the body or other object is placed.

115 It will be observed that the combustion-chambers are arranged in such manner in the oven or heating-space that heat can radiate freely from each side of the prisms and that all this radiated heat can be made effective in 120 heating the oven or other heating-chamber.

It must be understood that direct concentration of the heat at any one point in the combustion-chamber is highly objectionable 125 and will result in only partial combustion of the gases passing through the chamber, since such gases expand when introduced into the chamber and cannot be confined to any especial portion of the chamber, so that if the heat is directly concentrated only a small portion of the gases will be subjected to the concentrated rays, and the greater portion thereof will pass from the chamber unconsumed. Furthermore, as shown in Figs. 2 and 3, the

arrangement of the three prism-shaped combustion-chambers produces a fourth combustion-chamber of prism shape, in which the body to be incinerated is centrally arranged and receives the full direct action of the heat radiated from the opposing faces of the prism, as well as the indirect action of the heat radiated from the other faces of such prism. In addition to this, when the body which is being incinerated is brought to excessively high temperature and begins to exhale gases these gases are consumed and tend to produce still greater heat in the incinerating-chamber, sufficient air to promote combustion being admitted through the air-inlet N.

Now, having described my invention, what I claim as new, and desire to secure by Letters Patent, is—

1. A stove or furnace provided with a combustion-chamber consisting of a hollow triangular prism.

2. The combination of the fire-box having an air-inlet thereinto; a hollow triangular combustion-prism communicating with such fire-box through a contracted opening in the end of the prism and having a suitable outlet for the products of combustion at the other end of the prism, and an air-inlet into the prism at the front end thereof.

3. In a burning and heating appliance, the triangular combustion-prism provided with the contracted openings in its ends substantially as set forth.

4. The combination of the fire-box having an air-inlet thereinto; the combustion-prisms respectively having an outlet at one end and communicating at the other end with the fire-box and arranged side by side with a space between them to form a heating or incinerating chamber; air-inlets into the prisms; and the case inclosing the prisms.

5. The combination of the fire-box having an air-inlet thereinto; the three triangular combustion-prisms communicating with the

fire-box and arranged with a space between them to form a heating or incinerating chamber and respectively provided with an outlet for the products of combustion; an inclosing case around such prisms; an air-inlet into the heating or incinerating chamber; and an opening communicating between such chamber and the upper combustion-prism.

6. The combination of the fire-box having an air-inlet thereinto; the auxiliary combustion-chambers communicating with the fire-box and arranged with a space between them to form a heating or incinerating chamber and respectively provided with an outlet for the products of combustion; an inclosing case around such chambers; an air-inlet into the heating or incinerating chamber; and an opening communicating between such chamber and the upper combustion-chamber.

7. A furnace having between its fire-box and chimney a combustion-chamber which consists of a hollow triangular prism provided in each of its ends with a centrally-arranged circular opening inscribed within a triangle which is approximately one-fourth the cross-sectional area of such prism, and which openings communicate respectively with the fire-box and chimney.

8. A furnace provided with an incinerating-chamber and having therein between its fire-box and chimney three combustion-chambers arranged in a triangular figure and each consisting of a hollow triangular prism provided in its ends respectively with the centrally-arranged circular opening inscribed within a triangle which is approximately one-fourth the cross-sectional area of such prism, and which openings communicate respectively with the fire-box and chimney.

HORACE S. GARR.
